TOOL FOR SECURING TILE TO WALL OR
SIMILAR SURFACE

Arthur F. Leis, Dayton, Ohio

Original application June 10, 1948, Serial No.
32,127. Divided and this application April 4,
1950, Serial No. 153,916

2 Claims. (Cl. 81—15)

1

The present invention relates to a tool for securing tile to a wall or similar surface, such as for example, a floor or ceiling. More particularly, the present invention relates to a tool for bending a right angular flange of the prefabricated tile, such as a metal tile, over a shoulder, formed in the wall or a shoulder formed in a foundation sheet which is to be attached to a wall.

The tool of the present invention comprises a main body having a surface which is arranged to be brought into abutting relation with the outer surface of the tile. A pair of levers extend at right angles to the surface of the body, on opposite sides of the edges of the surface, and each of these levers has a portion which extends outwardly from the surface. These outwardly extending portions of the levers extend alongside of the flanges of the tile. The tool includes a mechanism for forcing these extending portions inwardly or toward one another for bending the flanges of the tile inwardly and about the shoulder in the wall to which the tile is to be attached.

More specifically, this movement of the levers is obtained by spreading the pivotal connections of the levers, causing the outwardly extending portions of the levers to be moved toward one another.

Still more specifically, the levers are yieldingly urged toward one another so as to grasp the opposite flanges of the tile for holding the tile on the tool.

Further objects and advantages of the present invention will be apparent from the following description, reference being had to the accompanying drawings wherein a preferred form of the embodiment of the invention is clearly shown.

In the drawings:

Fig. 1 is a perspective view of the improved tool;

Fig. 2 is a vertical sectional view taken through the center of the tool;

Fig. 3 is a perspective view of a tile with which the tool is used;

Fig. 4 is a front view of a wall or a foundation sheet having grooves cut therein for receiving the flanges of the tile; and

Fig. 5 is a fragmentary, vertical sectional view showing one of the tiles in position and showing a lower fragmentary portion of the tool, and showing another tile which has been clamped in position by the tool.

Referring to the drawings, the tool comprises a main body or plate 81, to the center of which there is secured a post 82. The post 82 is enlarged as at 83 so that it may be readily connected by bolts or screws with the plate 81. In the in-

stant embodiment, the plate 81 is formed with four slots adjacent each side thereof, two of these slots 84 and 85 being shown in Fig. 2. Levers 86, 87, 88 and 89 extend through the four slots. Guiding members, such as 91, 91B, 91C and 91D, made integral with the plate 81 or otherwise securely attached thereto, brace the levers 86, 87, 88 and 89 and serve as stops for normally positioning said levers. The levers 86, 87, 88 and 89 are secured respectively to supporting members 93, 94, 95 and 96 each having a pair of ears. The member 96 has ears 101 and 102. The member 94 has ears 103 and 103A. The member 93 has ears 104 and 104A. Ears 97 and 98 are pivotally attached to a toggle link 105. Likewise ears 101 and 102 are pivotally attached to a toggle link 107. Ears 104 and 104A are pivotally attached to a toggle link 108. Ears 103 and 103A are pivotally attached to a toggle link 110. In each instance the attachment is by a pivot 118. The toggle links 105, 107, 108 and 110 are all connected to a collar 109 formed as a part of a sleeve 111 surrounding the post 82. Extending snugly through opposed circular openings in the sleeve 111 is a pin 112 which also extends through a horizontal elongated slot 113 formed in the post 82. Secured to the upper end of the post 82 is a handle 114 by means of which the post may be held.

Suitable means is provided for yieldingly urging the free ends of levers 86, 87, 88 and 89 inwardly, that is, toward one another. This yielding means includes wires 115 and springs 115A. Holes 117 are drilled in each of the levers for receiving the wires 115, the ends of the wires being connected with a spring 115A.

The part of the post 82, lying above the slot 113 thereof, is hollow and contains a spring 116. This spring extends into the slot and engages the upper part of pin 112 and thereby yieldingly urges the sleeve 111 to its lowest position, as shown in Fig. 2.

It will be observed that the free ends of the levers 86, 87, 88 and 89 extend at right angles to the bottom surface and on opposite sides of the edges of the surface, and each of these levers has a portion extending below the surface. In operation, the outer surface of the tile, such as, for example, the tile shown in Fig. 3, is pressed against the bottom surface of plate 81 and positioned within the ends for the extending portions of the levers. The springs 115A maintain the levers in gripping contact with the tile so as to hold it in position against the bottom surface of the plate 81.

The tool described in the present invention is

particularly designed for use in connection with tile having right angular flanges along the side edges thereof. Several forms of this type of tile are shown in my co-pending application Serial No. 32,127, filed June 10, 1948, of which the present application is a division. An example of such tile is shown in Fig. 3 in which the tile 53 is formed with a main or outer surface 54, inclined portions 55, 56, 57 and 58 and each of the four edges is provided with a flange, two of which are illustrated at 59 and 60. The flanges are formed with a plurality of holes such as 61 which form a weakened line extending longitudinally of the flanges, that is, parallel to the edge of the flange, parallel to the junction of the flange with the inclined portion and parallel with the edge of the main surface.

The tile is to be secured in grooves preformed in the wall or the foundation sheet which is to be secured to the wall. The wall or foundation sheet 10 is formed with a plurality of horizontal parallel grooves 11, 12, 13 and 14 which are intersected by a plurality of vertical parallel grooves 16A, 16B, 16C, 16D and 16E, all perpendicular to the first mentioned set of grooves. Preferably these grooves are of the dovetail type as shown in Fig. 5, forming undercut shoulders 50, bevelled portions 48 on the outer surface, and the walls 49 forming the neck to the dovetail portion being at substantially right angles to the outer main surface of the wall.

The flanges, such as 59 and 60, on all four edges of the tile 54 are resiliently gripped by the levers 86, 87, 88 and 89. The tile and tool are then placed over the wall with the flanges and the extending portions of the levers of the tool into the appropriate groove such as, for example, grooves 12, 16C, 13 and 16D. Force is then exerted downwardly on the tool through the handle 114, as viewed in Fig. 5, and simultaneously, the pin 112 is pulled toward the handle 114. This raises the sleeve 111 and the collar 109, causing spreading of the toggle links 105, 107, 108 and 110 and consequently spreading the pivots of the levers 86, 87, 88 and 89. This spreading of the pivots 118 of the levers will cause the levers to pivot about the plate 81, whereby the outwardly extending or free ends of the levers will be forced inwardly with the consequent result of the flanges on the tile being bent toward one another into locking engagement with the shoulders 50 of the dovetail grooves. The weakened portions of the flanges are substantially parallel with the lower edge of the wall 49 of the neck of the groove. The tile is preferably formed of a ductile metal which, after being bent into firm and snug relation with the shoulders 50, remains in gripping relation with the shoulder.

After a tile is secured in position, as previously described, the operator releases the pin 112 and the spring 116 forces the sleeves 111 and 109 downwardly (as viewed in Fig. 2) and then the tool is withdrawn.

The present invention is particularly suitable as a tool for carrying out the invention described in the parent application Serial No. 32,127, filed June 10, 1948. Obviously from the foregoing, all four flanges of the tile are clamped in position simultaneously. It will of course be understood that one of the pairs of levers, for example, levers 88 and 89, may be omitted when it is desirable to simultaneously secure only opposite pairs of the flanges in position.

While the form of embodiment of the present invention as herein disclosed constitutes a pre-

fferred form, it is to be understood that other forms might be adopted, all coming within the scope of the claims which follow:

I claim:

1. A tool for securing a tile to a wall or similar surface, comprising a body having a bottom surface for abutting the outer face of the tile to be secured in position, said body having a pair of slots adjacent opposite edges of said bottom surface of the body; a pair of levers fulcrumed in the slot, one of said levers extending from above said bottom surface, through one of the slots and extending below said bottom surface, the other lever being similarly positioned with respect to the other of said slots; a post secured substantially centrally of the body and extending upward of the body; a handle on the top of the post; a sleeve mounted for longitudinal slideable movement on and guided by the post, the top of the sleeve terminating below the handle thereby providing clearance for upward sliding of the sleeve on the post and the bottom of the sleeve terminating below the top of the levers; toggle links pivotally connected with the upper parts of the levers and pivotally connected to the bottom of the sleeve, the last mentioned pivotal connections lying in a horizontal plane below the first mentioned pivotal connections, said toggle links being thereby adapted to actuate the levers for moving the lower ends of the levers toward one another upon upward sliding of the sleeve; and a handle for pulling the sleeve upwardly.

2. A tool for securing a tile to a wall or similar surface, comprising a body having a bottom surface for abutting the outer face of the tile to be secured in position, said body having a pair of slots adjacent opposite edges of said bottom surface of the body; a pair of levers fulcrumed in the slot, one of said levers extending from above said bottom surface, through one of the slots and extending below said bottom surface, the other lever being similarly positioned with respect to the other of said slots; a post secured substantially centrally of the body and extending upwardly of the body; a handle on the top of the post; a sleeve mounted for longitudinal slideable movement on and guided by the post, the top of the sleeve terminating below the handle thereby providing clearance for upward sliding of the sleeve on the post and the bottom of the sleeve terminating below the top of the levers; toggle links pivotally connected with the upper parts of the levers and pivotally connected to the bottom of the sleeve, the last mentioned pivotal connections lying in a horizontal plane below the first mentioned pivotal connections, said toggle links being thereby adapted to actuate the levers for moving the lower ends of the levers toward one another upon upward sliding of the sleeve; a spring interposed between the post and sleeve yieldingly urging the sleeve downwardly; and a handle for pulling the sleeve upwardly.
